Dec. 25

The nature of my invention consists in the peculiar con-
figuration and ornamental carved work of the under surface
of the side plates of the stove.

It is impossible to describe accurately in language the
ornamental carvings on the surface of the plates but the same
is represented as accurately as possible in the side plate of
the Engraving or drawing hereto annexed and by the pattern
or model herewith transmitted. The plate may be of
any convenient size and consists of a base or lower sec-
tion extending a little less than half the height of the plate
face, with ornamental carvings somewhat resembling pillars
five in number (may be more or less) small at the bottom
extending in width & projecting in front in equal propor-
tions as they ascend till they reach about three fourths the
height of the section when they suddenly diminish in width
and recede from the front to the surface of the body
of the plate, and are fluted in like proportion as is shown
in the drawing. Between each pair of these quasi pillars
or columns is a fancy spring, and an upper section con-
tinues the rest of the plate (except a border across the
top) ornamented with carvings representing a bunch of
melons and grapes, also a fancy border across the top
as represented in the drawings.

What I claim as my invention and desire to secure
by letters patent is the peculiar style of ornamental car-
ving on the surface of the plate and the peculiar ele-
vations and depressions of the surface as represented
in the drawing and by the model.
